Primary Examiner — David Muller

Assistant Examiner — Nathan Johnston

(57) **CLAIM**

The ornamental design for a curved hypodermic needle, as shown and described.

DESCRIPTION

FIG. 1 is a perspective view of my new design, wherein the needle is bent towards the tube;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a perspective view of second embodiment of my new design, wherein the needle is bent away from the tube;

FIG. 9 is a front elevation view thereof;

FIG. 10 is a back elevation view thereof;

FIG. 11 is a top plan view thereof;

FIG. 12 is a bottom plan view thereof;

FIG. 13 is a right side elevation view thereof; and,

FIG. 14 is a left side elevation view thereof.

1 Claim, 14 Drawing Sheets
